This is a continuation-in-part of my copending application, Serial Number 722,613, filed January 17, 1947, for a "Two-Speed Hydraulic Ram." The present application is also a continuation-in-part of my copending application, Serial Number 722,614, filed January 17, 1947, for a "Hydraulic Control Valve."

UNITED STATES PATENT OFFICE

Patented August 1, 1950. Serial No. 2,517,164. Filed January 17, 1947.

TWO-SPEED HYDRAULIC RAM

Bruno F. Arps, New Holstein, Wis.

Application February 19, 1947, Serial No. 729,555.

5 Claims. (Cl. 60—97)

1 The present invention relates to means for controlling and operating a two speed ram, the controlling means comprising a valve box, controlling levers for the same, a regulator and a novel arrangement of rams.

The present invention is a continuation in part of my copending application, Serial Number 722,613, filed January 17, 1947, Hydraulic Control Valve.

The principal object of the present invention is to provide a dual speed and dual power ram comprising a relatively large diameter single acting ram and a relatively small in diameter double acting ram, wherein the rams are mechanically connected together for simultaneous movement in the same direction and provide a valve box and regulator for controlling these rams whereby the double acting ram will raise and lower the single acting ram at relatively high speed, and the single acting ram will extend at relatively low speed but having greater power, the operations being at all times under the direct control of the operator through three controlling levers.

A further object of the present invention is to provide a hydraulic system whereby the operator may by operating one of two levers, move the rams at high speed in either direction at will and when desired can by the simple movement of another lever extend the rams at low speed with greatly increased lifting power.

To these and other useful ends my invention consists of parts and combinations of parts or their equivalents and mode of operation as hereinafter described and claimed and shown in the accompanying drawings in which:

Fig. 1 is a perspective view of my improved two speed hydraulic ram system.

Fig. 2 is a diagrammatic drawing illustrating the device as shown in Figure 1.

As thus illustrated the valve box is designated in its entirety by reference character A the regulator by reference character B, the double acting ram is designated by reference character C and the single acting ram is designated by reference character D. The hydraulic pump is designated by reference character E and the oil tank or sump is designated by reference character F.

Member A is somewhat similar to member 14 in my copending application, member B is somewhat similar to member 20 in my copending application.

Pump E has a suction pipe 10 leading from sump F and a discharge pipe 11 which leads to valve box A as illustrated, a pipe 12 forms a

discharge connection from member A to sump F. Regulator B may be mounted within the main valve box A or made in a separate unit as illustrated in Figure 1. Member A is provided with an inlet passageway 13 and an outlet passageway 14, each being connected to pipes 11 and 12 as illustrated.

2 I provide three spaced passageways 15, 16 and 17, which extend from passageway 13 to passageway 14. The bottom of each of these passageways is adapted to form a seat for balls 18. The balls being held on their seats by means of springs 19. The upper ends of the passageways are each provided with seats for the reception of balls 20. In each passageway I provide a skeleton piston 21 having a length about as illustrated which is adapted to hold balls 20 from their seats when balls 18 are seated. I provide a port 22 having a seat at its upper end on which ball 23 is held by spring 24. Thus it will be seen that ball 23 will act as a relief valve between inlet and outlet passageways 13 and 14. I provide means for operating the valves in box A as follows:

3 A bracket 30 is held for vertical movement to a post 31 mounted on member A, by means of links 32 and 33, whereby member 30 may move vertically, I provide three control levers 34, 35 and 36 each of which are hinged to member 30 as at 37. I provide three slidably mounted pins 38 which are adapted to rest on balls 20 and contact levers 34, 35 and 36 as at 39 when balls 20 are held in their raised position by springs 19.

4 I provide a passageway 40 which extends from inlet passageway 13 to outlet passageway 14, the upper end being provided with a seat for the reception of a ball 41. Member 33 has a forwardly extending arm 42. I provide a slidably mounted pin 43 adapted to contact member 42 as at 44 when ball 41 is raised as illustrated. It will be seen that normally oil is free to pass through passageway 40 from inlet passageway 13 to outlet passageway 14 unless ball 41 is seated. The operation of the levers is as follows:

5 When any one of levers 34, 35 or 36 is pulled, for example, to the left as in Figure 2, one of rods 38 will be pushed downward and a skeleton piston 21 will be pushed downward until a ball 20 is seated and a ball 18 is moved from its seat. Movement of any lever to the left first causes the seating of its associated ball valve 20 and the unseating of associated ball valve 18. A further movement of the lever to the left after ball 20 has been seated will cause movement of member

30 about its pivots on post 31. This movement

of member 30 causes a clockwise movement of member 42 about its pivot on post 31, thus causing member 42 to depress rod 43 to force ball 41 on its seat.

Thus when a lever is pulled to the left, passageway 40 will be closed and a passageway 15, 16 or 17 will be open to inlet passageway 13 and the oil must then, because of ball 41 being seated, pass into a tube connection to the regulator for a purpose which will hereinafter appear. It will be seen, for example, that when lever 36 is pulled to the left passageway 15 will be open to inlet passageway 13, when lever 35 is pulled to the left passageway 16 will be open to inlet passageway 13 and when lever 34 is pulled to the left, passageway 17 will be open to inlet passageway 13 and in each instance the passageway 40 to outlet passageway 14 will be closed.

Member B has a cylinder 50 in which pistons 51-51 are slidably mounted, each piston having outer projections 52 and 53 and inward projections 54 and 55. Passageway 15 has a pipe connection 56 to the left end of cylinder 50 and passageway 17 has a pipe connection 57 to the right end of cylinder 50. Passageway 16 has a pipe connection 73 to the center of cylinder 50.

Cylinder 50 on its left end has an outlet 60 with a seat on which a ball 61 is held by means of spring 62. On the right end, cylinder 50 has an outlet 63 with a seat on which ball 64 is held by means of a spring 62. It will be seen therefore that oil pressure from passageway 15 will move pistons 51 to the right and move ball 64 from its seat and that oil pressure from passageway 17 through pipe 57 will move pistons 51 to the left and move ball 61 from its seat for a purpose which will now be explained.

I provide projections 62' which are adapted to limit the movement of balls 61 and 64, thus to keep pistons 51 within bounds.

Ram D has a piston 70 and ram C has a piston 71, these pistons being connected together by means of a rod 72. Cylinder 50 has a pipe connection 74 to the bottom of ram D. The outlet side of ball 61 has a pipe connection 75 to the top of the cylinder of ram C and the outlet chamber of ball 64 has a pipe connection 76 to the bottom of ram C.

It will be seen that, for example, when lever 36 is pulled to the left oil pressure will accumulate in the left end of cylinder 50, this will move pistons 51 to the right and lift ball 64 forcing piston 71 to move downward because of the pressure from passageway 15, this pressure lifting ball 61 from its seat the oil then flowing through pipe 75 into the top of member C.

Thus piston 71 will be forced down, oil from the bottom of member D will be free to flow through pipe 14 into cylinder 50 and from this cylinder through pipe 73 into passageway 16 and then into outlet passageway 14. During this time since valve 64 is held from its seat oil will be free to flow from the bottom of ram C through pipes 76 and 57 into passageway 17 and then into outlet passageway 14.

Clearly ram C may be extended or retracted by pulling to the left either lever 34 or 36. When lever 34 is pulled to the left its balls 20 and 41 will be seated and oil will flow from passageway 17 to the right end of cylinder 50 through pipe 57, moving pistons 51 to the left so as to open valve 61 and then to the bottom of member C raising pistons 71 and 70, the oil from the top of member C will flow through pipe 75 to cylinder 50 and then through pipe 56 and then to outlet

passageway 14 through passageway 15, and that when piston 71 is moved piston 70 will be free to follow.

When it is desired to extend the rams at low speed and high power, lever 35 is pulled, when this occurs piston 71 will be free to move because the pressure between pistons 51 will open valves 61 and 64, leaving piston 71 free to move.

Thus it will be seen that rapid movement of piston 71 in either direction is under the complete control of the operator and that this piston 71 may be stopped in any medial position because when the pressure used for moving this piston is shut off valves 61 and 64 will be closed automatically and the rams will be held in position until any one of the three levers is moved.

I provide means to cushion or release excessive pressure in the connection from pipes 75 and 76 as follows:

20 Devices moved by rams are frequently quite heavy; therefore a sudden closing of a valve while the rams are moving rapidly might cause considerable pressure in one of these pipes. Valves 80-80 are held on their seats by means of springs 81-81, each valve having ports 82-82 which lead from pipes 75 and 76, springs 81 being heavy enough to hold the valves on their seats against normal operating pressure, however a serious increase in pressure will move either of these valves 30 off their seats, thus to protect the device against injury, by permitting the excessive pressure to flow into cylinder 50 through outlets 83.

It will be seen that by manipulating one of the levers the rams may be moved at will either at high speed and medium power or at low speed for maximum lifting power.

Having thus shown and described my invention, I claim:

1. A two speed hydraulic ram comprising, a 40 pair of rams, a valve box and a regulator, a source of oil pressure having connections to said valve box, said pair of rams comprising a single acting ram and a relatively smaller diameter double acting ram mechanically connected together for simultaneous movement in the same direction, operating connections between said valve box and regulator and between the regulator and rams, valves in said valve box and regulator, manually operated extending and retracting levers mounted on said valve box with means associated with said valves whereby said double acting ram may be extended and retracted, another manually operated lever mounted on said valve box with means associated with said valves whereby said 45 single acting ram may be extended, automatically operated means in said regulator whereby when fluid is supplied to or exhausted from said single acting ram to extend or retract said ram, said double acting ram will be hydraulically free to extend or retract and means whereby when fluid pressure is supplied to said double acting ram to extend or retract said ram, said single acting ram will be hydraulically free to extend or retract.

2. A device as recited in claim 1 including, 55 said automatic means comprising, outlet check valves in the ends of said regulator, a piston chamber between said outlet check valves with the inlet side of the check valve extending directly into the piston chamber, two pistons slidably 60 mounted in said piston chamber having projections with means whereby when a piston approaches an outlet check valve the valve will be opened, the single acting ram operating connection being made between said pistons, whereby 70 when pressure is directed to extend the single

acting ram the pistons will move outward and open both said check valves to provide a free passageway between the ends of the double acting ram and said outlet passageway.

3. In combination, a hydraulic pump having a sump, a single acting ram and a double acting ram mechanically connected together for simultaneous movement in the same direction, a valve box having inlet and outlet passageways, inlet and outlet pipes from said passageways to said pump and sump, a regulator, operating connections between said valve box and regulator and between the regulator and single and double acting rams, a manually operated lever having an operating connection to certain valves located in said valve box to cause their operation to positions in which they direct fluid pressure to extend said single acting ram, two other manually operated levers each having connections to certain other valves located in said valve box to cause their operation to positions in which they direct fluid pressure to said double acting ram to cause its extension or retraction, means whereby when said single acting ram is being extended said double acting ram will be permitted hydraulically to extend and whereby when said double acting ram is extended or retracted said single acting ram will be freed hydraulically to extend or retract.

4. In combination, a hydraulic pump having a sump, a single acting ram and a double acting ram mechanically connected together for simultaneous movement in the same direction, a valve box having inlet and outlet passageways, inlet and outlet pipes from said passageways to said pump and sump, a regulator, valves in said valve box and regulator, operating connections between said valve box and regulator and between said regulator and said rams, a manually operated lever having operating connections to certain valves for operating said valves so as to direct pressure fluid to extend said single acting ram, two manually operated levers having connections to certain valves to cause their operation so as to direct pressure fluid to extend or retract said

double acting ram, said regulator having a medially positioned cylinder with two spaced independent pistons, outlet spring held valves in opposite ends of said regulator, said cylinder between said pistons being operatively connected to said single acting ram and means whereby oil pressure for operating the single acting ram will move the pistons apart and open said outlet valves providing free oil passageways between the double acting ram and said outlet passageway, means whereby said single acting ram is left free hydraulically to move in either direction when its extending lever is in neutral position.

5. In an automatic regulator of the character described comprising, an elongated housing having outlet valves in the ends thereof, a piston chamber between said valves positioned concentric with the valves and having direct openings to the inlet sides of the valves, separate ports leading into the end of said piston chamber and a third port leading into the center of the piston chamber, two spaced pistons independently slidably mounted in said piston chamber having projections whereby when one or both pistons approach a check valve, the check valve will be opened, an outlet in said piston chamber at the center thereof, whereby when pressure is added to said third port, said pistons will be caused to move apart and open both check valves and whereby when pressure is added to either end of the piston chamber the pistons will be caused to move toward and open the check valve approached.
